Augustine
ATTORNEY

UNITED STATES PATENT OFFICE.

HENRY C. SWAN, OF OSHKOSH, WISCONSIN.

DESIGN FOR A BODY-HANGER FOR VEHICLES.

SPECIFICATION forming part of Design No. 32,928, dated July 10, 1900.

Application filed March 12, 1900. Serial No. 8,416. Term of patent 14 years.

To all whom it may concern:

Be it known that I, HENRY C. SWAN, a citizen of the United States of America, residing at Oshkosh, Winnebago county, State of Wisconsin, have invented and produced a new and original Design for a Body-Hanger for Vehicles, of which the following is a specification.

In the accompanying drawings, Figure 1 is a view in perspective of a body-hanger for vehicles, showing my new design. Fig. 2 represents a cross-section of the transverse bar of the body-hanger on the line 2 2 of Fig. 1.

As shown in the drawings, the leading or material feature of my design consists in the new and novel shape and configuration of the body-hanger.

The body-hanger is provided with body-bearings A, that are connected by curved arms B with a transverse bar C. The end portions

c of the transverse bar are oval or elliptical in shape and have their major axes approximately at right angles to the plane of the body-bearings. The central portion c' of the bar is enlarged, and its bottom c² is slightly concaved. The connecting-arms B are approximately S-shaped and are formed integral with the body-bearings and the transverse bar.

What I claim as new, and desire to secure by Letters Patent, is—

The design for a body-hanger for vehicles substantially as shown and described.

In witness whereof I sign this application; in the presence of two witnesses, this 9th day of March, 1900.

HENRY C. SWAN.
